BOOKBINDER

Frank Amato, New York, N. Y., assignor to
 Kamket Corporation, New York, N. Y., a corporation of New York

Application December 21, 1935, Serial No. 55,556

4 Claims. (Cl. 129—23)

This invention relates to book binders and more particularly to that class of book binders in which an outer folder or cover is provided with means for accommodating and holding loose sheets which are attachable or detachable, at will, from the cover and the binding means.

The main object of this invention is to provide an inexpensive book binder, the folder or cover of which can be packed and shipped flat, apart from the binding element, and in which the binding element may be slid into position with respect to the cover and in such position being permanently related to the cover but removable therefrom. The binder element in association with the folder or cover, is manipulatable by a swinging or rolling motion, to a position for inserting sheets therein and adapted to be placed in a position in which the sheets under ordinary manipulation, as in a book, will not be displaced. To utilize the binder of this invention it is not necessary to have any special tools for opening the binder, or catches to lock the sheets in the binding element. Other advantages of this invention will appear from the following description.

In the drawing, Fig. 1 is a top view of the open folder or cover with the binding element positioned therein, but without inserted pages; Fig. 2 is a top view of the open folder or cover with the binding element positioned therein, illustrating the position and relation of the binding element with a loose sheet as the two are being associated; Fig. 3 is a cross section of the book binder with a number of sheets secured to the binder element, with the binder element shown in the same position as in Fig. 2, and Fig. 4 is a cross section of the book binder with the folder or cover closed.

The cover or folder 1 preferably comprises two members 2 and 3, member 2 forming the top cover of the folder or cover, and member 3 forming the bottom cover. It is preferred to utilize both a top and bottom cover, but the top cover may be dispensed with if it is not desirous of covering the sheets comprising the book. The bottom cover 3 is provided with a support 4 preferably made of fairly stiff, but flexible, cardboard or other sheet material. The support 4 is secured to the bottom cover by suitable fastening means, for instance, hollow rivets 5, positioned inside of the outside edge of the support 4, thereby providing a flexible portion 6 which is part of the support 4 and which flexible section lies between the outer edge of the support 4 and a line drawn through the rivets 5. It is preferred to extend the support

on both sides of the fastening means 5, thereby providing a line of flexion of the portion 6, along the line of rivets 5 and support for the structure by that portion of the support 4 lying opposite the flexible portion 6. The binder element 7 is preferably made of wire or other stock material, which is bent into a plurality of sheet-retaining members 8, preferably of ring conformation, tongues 9, and tie members 10. In forming the binder element 7 of stock material such as wire, it is evident that the binder element may be made by bending operations entirely, in practically endless lengths and cut to provide the particular number of rings required for the size of the book binder. In the course of formation of the binding element, each sheet-retaining member or ring 8 is made up of a double thickness of wire, or other stock material, and the tongues 9 are likewise made of double thickness of stock material, while the tie members 10 are made of single thickness stock material. An examination of Fig. 2 shows the course of the stock material as it is bent into configuration, the first convolution 11 terminating in one leg 12 of the tongue 9, the stock material after the leg 12 is formed, being bent at 13 to form a second leg 14. The legs 12 and 14 lie in engaging position so as to form two closely aligned members making up the tongue 9. The second leg 14 terminates and merges with the convolution 15 of the sheet-retaining ring 8 and the two convolutions 11 and 15 likewise lie in engagement, to provide, for all practical purposes, but a single sheet-retaining member made up of two engaging juxtaposed convolutions. The second convolution 15 terminates in the tie member 10 which unites adjoining convolutions of the series of sheet-retaining members. In the course of construction of the binding element 7, the tongues 9 do not partake of the curvature of the rings 8 and do not engage the ends of the rings associated with the tie members 10, but are spaced therefrom to provide openings 17. The tongues 9 are relatively short and extend a short distance beyond the plane in which the inner edges of the rings 8 lie, thereby defining the openings 17, on the underside, by the tongue 9, the rings 8 and the bend in the tie member 10 where it joins, at 16, a convolution of one of the rings 8. The support 4 is provided with a plurality of perforations 18 equal in number to the number of tongues and ring members constituting the binding element. These perforations 18 are formed just inside of the free edge of the portion 6, in order that the distance from such free edge to the perforations is not greater than 55.

than the openings 17 in the rings 8, to permit free passage of the edge of the flexible portion 6 through such openings 17. The binding element is positioned with respect to the folder and the support 4 by inserting the tongues through the perforations 18, as shown in Fig. 2, and then turning the entire binder element about its central axis and tucking tongues 9 beneath portion 6 so that the binder element assumes the position shown in Fig. 1. The support 4 provides a stiffening means for the bottom cover 3, but the flexible portion 6 is capable of movement by flexion toward and away from the inside face of the bottom cover 3. The length of the tongues 9 is less than the distance from the outer edge of the flexible portion 6 to line in which the fastening means or rivets 5 lie. That portion of the folder which will constitute the back of the book is preferably scored with a series of parallel lines 19 in order to provide a back for the book and permit such back to follow the general contour of the ring members 8.

The binder element is assembled in the cover in association with the support 4 by inserting the ends of the tongues 9, from the underside of the flexible portion 6, into the perforations 18 in the support 4. The entire binding element is then pushed upwardly so that the tongues slide completely through the perforations 18 and the free edge of the flexible portion 6 slides through the openings 17 into engagement with the rings 8, as illustrated on an enlarged scale in Fig. 3. The tongues are then pushed toward the left, which causes rotation of the entire binder element 7. Continued rotation of the binder element through the perforations 18, causes engagement of the ends 13 of the tongues 9 with the inside of the top cover, the tongues riding over the inside of the cover and lifting the free end of the flexible portion 6 (shown in Fig. 4) from the bottom cover 3 and the insertion of the tongues into the space formed between the bottom cover 3 and the underside of the flexible portion 6. The final relation of the parts is shown in Fig. 1, in which the tongues are tucked beneath the flexible portion 6 and the underside of the flexible portion 6 engaging the tie members 10. When it is desirable to insert a sheet in the folder, the top cover 2 is thrown to the left and some of the ring members 8 are grasped and rolled toward the right. This action causes the support 4 to flex and the ends 13 of the tongues 9 to ride over scorings 19 and continued rolling of the binder element 7 will ultimately bring the tongues into the position shown in Fig. 2, in which they stand substantially upright. This motion brings the openings 17 from the covered position shown in Fig. 1, to the exposed position shown in Fig. 2. The ends 13 of the tongues are inserted through the perforations 20 in the sheets which are to be added to the book, until the sheets lie approximately in the position shown in Fig. 3, having passed through the openings 17 in the binder element. The binder element is now rotated or rolled toward the left, the edges 13 thereof riding over the scorings 19 while the flexible portion 6 flexes upwardly. Continued rotation or rolling of the element causes the tongues to again pass beneath the flexible portion 6, thereby covering the openings 17 beneath the flexible portion 6, as shown in Figs. 1 and 4. The entire weight or burden of the sheets carried by the support 4 and the folder 1 engaging its top and bottom covers 2 and 3, merely provide covers for the sheets and the binding element.

The entire folder is preferably made so as to be flexible throughout, reinforced, and slightly stiffened only by the support 4 which extends substantially lengthwise of the lower cover with its outer edge close to that portion of the folder 5 which forms the back of the book. The tongues 9 are extremely short in order that said tongues will properly function with the other elements of the invention. The length of the tongues is limited to extend just beyond the vertical plane in 10 which the openings 17 and the tie bars 10 lie as seen in Fig. 4. Tongues of such character, when the book is completed, extend just beneath the free edge of the support 4, permitting the manipulation of the sheets of the book in the normal manner without the escape of the sheets from engagement with the ring-like members, but nevertheless permitting the tongues to be rotated or swung to open position for the ready insertion 15 of sheets over the exposed tongues and through 20 the ring openings.

I claim:

1. A book binder comprising a backing, a support, fastening means securing the support to said backing, said fastening means being positioned inwardly of the outside edge of said support, the portion of the support from the outside edge thereof to said fastening means being flexible and free of said backing, the said support, 25 inwardly of the outside edge, but in close proximity thereto, being provided with a plurality of perforations, a binder element comprising a plurality of sheet-supporting members, each sheet-supporting member comprising an open ring-like member, a tongue extending beyond the opening, 30 said tongue being shorter than the distance from the outside edge of said support to the fastening means, a connecting member extending from one ring-like member to the next adjoining ring-like member, said binder element being carried by said support with the tongues inserted through said perforations and the outside edge of said support lying within said ring-like members inside of the openings thereof, said binder element being rotatably supported on said support, and said 35 tongues in normal position being located between said flexible portion and said backing, said tongues being positionable to a substantially upright position by rotation of said binder element 40 from normal position, exposing said tongues and said openings, whereby sheets provided with perforations may be inserted on said binder element, said binder element being rotatable to position said tongues beneath said flexible portion to cover and conceal said tongues and said openings. 45

2. A sheet binder comprising a top cover, a bottom cover, a back, all adapted to receive a plurality of sheets provided with perforations, a support, fastening means securing the support to said bottom cover, said fastening means being positioned inwardly of the outside edge of said support, the portion of the support from the outside edge thereof to said fastening means being flexible and free of said bottom cover, the said support, 50 inwardly of the outside edge, but in close proximity thereto, being provided with a plurality of perforations, a binder element comprising a plurality of sheet-supporting members, each sheet-supporting member comprising an open ring-like member, a tongue extending beyond the opening, 55 said tongue being shorter than the distance from the outside edge of said support to the fastening means, a connecting member extending from one ring-like member to the next adjoining ring-like member, said binder ele- 70

ment being carried by said support with the ring-like members passing through the perforations in said support and with the tongues extending beyond said perforations and the outside edge of 5 said support lying within said ring-like members inside of the openings thereof, said plurality of sheets being adapted to be carried by said binder element with the tongues inserted through the perforations in said sheets, said binder element 10 being rotatably supported on said support, and said tongues, in normal position, being located between said flexible portion and said bottom cover, said tongues being positionable to a substantially upright position by rotation of said 15 binder element from normal position, exposing said tongues and said openings, whereby additional sheets, provided with perforations, may be inserted on said binder element, said binder element being rotatable to position said tongues beneath said flexible portion to cover and conceal said tongues and said openings and permit 20 said sheets to be paged without escape from said binder element.

3. A book binder comprising a backing, a support secured to the backing, one edge of the support being provided with perforations, a binder element comprising a plurality of sheet-supporting members, each sheet-supporting member comprising a ring-like member, a tongue, an 25 opening in said ring-line member, said ring-like members and said tongues being made of continuous bent stock material, a tie member extending from one ring-like member to the adjoining ring-like member, the opening being defined by a tongue and the end of the ring-like member, said tongue extending a short distance beyond 30 the opening and providing means to guide the sheet to said ring-like member, said binder element being normally carried by said support with the ring-like members passing through the perforations in said support, with the tongues located beneath said support, said binder element being rotatably supported on said support, and when rotated from said normal position, said 35 tongues swinging from beneath said support and exposing their ends and said openings for threading and reception of sheets perforated along the edges thereof.

the ring-like members passing through the perforations in said support, with the tongues located beneath said support, said binder element being rotatably supported on said support, and when rotated from said normal position, said tongues 6 swinging from beneath said support and exposing their ends and said openings for threading and reception of sheets perforated along an edge thereof, said tongues, while being rotated to normal position, riding over said backing and raising one end of said support to provide a space 10 between said support and said backing for insertion of said tongues.

4. A book binder comprising a backing, a support secured to the backing, one edge of the support being provided with perforations, a binder element comprising a plurality of sheet-supporting members, each sheet-supporting member comprising a ring-like member, a tongue, an opening in said ring-like member, said ring-like 15 members and said tongues being made of continuous bent stock material, a tie member extending from one ring-like member to the adjoining ring-like member, the opening being defined by a tongue and the end of the ring-like member, said tongue extending a short distance beyond 20 the opening and providing means to guide the sheet to said ring-like member, said binder element being normally carried by said support with the ring-like members passing through the perforations in said support, with the tongues located beneath said support, said binder element being rotatably supported on said support, and when rotated from said normal position, said 25 tongues swinging from beneath said support and exposing their ends and said openings for threading and reception of sheets perforated along the edges thereof.

FRANK AMATO.
